RATCHET TOOL FOR ROTARY ATTACHMENTS

Arden B. MacNeill, 63 Riverview Ave.,
Waltham, Mass. 02154

Filed Feb. 21, 1966, Ser. No. 1,140

Term of patent 14 years

(Cl. D54—16)

Fig. 1

Fig. 2

Fig. 3

FIG. 1 is a plan view of a ratchet tool for rotary attachments showing my new design;

FIG. 2 is an end elevational view as seen from above FIG. 1; and

FIG. 3 is an end elevational view as seen from below FIG. 1.

The dominant features of my design reside in the portions shown in full lines.

I claim:

The ornamental design for a ratchet tool for rotary attachments, as shown and described.
